UNITED STATES PATENT OFFICE.

GEORGE W. PERKINS, OF BOSTON, MASSACHUSETTS, ASSIGNOR TO HEATON PENINSULAR BUTTON FASTENER COMPANY, OF GRAND RAPIDS, MICHIGAN, A CORPORATION OF MAINE.

BUTTON-FASTENING MACHINE.

1,297,726.

Specification of Letters Patent. Patented Mar. 18, 1919.

Application filed December 8, 1916. Serial No. 135,884.

To all whom it may concern:

Be it known that I, GEORGE W. PERKINS, a citizen of the United States, residing at Boston, county of Suffolk, State of Massachusetts, have invented a certain new and useful Improvement in Button-Fastening Machines, of which the following is a specification, reference being had therein to the accompanying drawings.

- 10 The invention relates to a machine for attaching buttons to shoes and other articles by metallic fasteners, and is especially intended for that class of such machines in which the fastener is formed from a wire 15 which is fed through the eye of the button, the wire then being formed into shape for the fastener, the button and attached fastener then being carried to a position to be secured to the shoe or other article.
- 20 One feature of the invention relates to an adjustable cover for the raceway and the means for raising and lowering it to adapt it to buttons of different sizes.

In Patent No. 1,070,170 dated August 12, 25 1913, granted on my application there was shown and described a carriage movable parallel with the raceway and provided with two slidable fingers movable with the carriage and movable laterally with relation to the carriage to position the button 30 for the threading movement of the fastener wire. One feature of the present invention relates to an improvement on said button fingers.

35 In the device shown in said patent the button fingers were formed with transversely concaved inner ends to grip the button head between them, but in the construction there shown the said ends were 40 concaved in such manner that the width of the entrance to the space between said jaws was the same as the width of the exit from said jaws. One feature of the present invention is to so form the concave ends of the 45 fingers that the width of the passage out from between the concave ends of said jaws on the lower side shall be greater than the width of the entrance between said fingers on the upper side for the purpose of more 50 readily releasing the said fingers from the button at the time of the return movement of the fingers.

Another feature of the invention is to form the concaved ends of said fingers some-

what under cut or backwardly sloping on 55 the under side so that the ends of the fingers on their upper sides will engage the rounded upper surface of the button head while the lower portion of the finger end retreats away from the button. 60

The invention will be fully understood from the following description taken in connection with the accompanying drawings and the novel features will be pointed out and clearly defined at the close of the specification. 65

In the drawings, Figure 1 is a side elevation partly in section of a portion of a raceway and connected parts embodying the invention and showing a portion of the operative parts therefor, the parts being shown in position where a button has been carried to the position for being threaded, the usual placer being omitted for the purpose of more clearly showing the parts which are 75 the subject of the present invention.

Fig. 2 is a plan view of the parts shown in Fig. 1, looking in the direction of the arrow on Fig. 1.

Fig. 3 is a section on line 3—3 of Fig. 2. 80

Fig. 4 is a section on line 4—4 of Fig. 2.

Fig. 5 is a plan view of the two button fingers detached.

Fig. 6 is a longitudinal section of one of the button fingers. 85

Fig. 7 is an enlarged detail view of one of the buttons of the form specially adapted for use with the machine.

Referring now to the drawings, 1 represents the raceway, and 2 the raceway cover, 90 the buttons 6 traveling down the raceway in the usual manner. The particular form of raceway, however, will be more particularly hereinafter described.

Any suitable form of mechanism for feeding the wire through the eye of the button and forming the loop and legs of the fastener and severing the blank of which the fastener is formed from the length of the wire may be employed, it not being deemed 100 necessary to show such mechanism here in detail. In the accompanying drawings a portion only of the mechanism is shown.

3 is an arbor on which the wire 4 rests after it has been threaded through the eye 105 5 of the button 6.

7 designates what is termed the former which forms the loop of the fastener and is

attached to a former holder 8 which is reciprocated by an arm 9 carried by a lever 10, said lever 10 being actuated by a suitable mechanism not shown. Said arm 9 engages 5 with a slot 11 in the former holder 8.

The legs of the fastener are formed by a slide 12 which is actuated by an arm 13 carried by a lever 14, said arm 13 engaging with an elongated slot 15 in the slide 12.

10 The lever 14 is actuated by mechanism not shown.

When the button is in the position for receiving the wire for the fastener, as shown in Fig. 1, a device called a placer is usually 15 employed to hold the button against movement during the feeding of the wire to the former for the fastener, but the placer is not shown in the drawings.

The particular form of button shown in 20 the drawings for illustration in connection with the machine is formed with a boss 16 on the under side of the head 6 of the button into which the shank of the button eye extends.

25 The raceway 1 is formed with a groove or channel extending lengthwise thereof and of sufficient depth to receive the boss and eye of the button while the under side of the head rests upon the side lips 17 of the race- 30 way. The outer part 18 of the groove in which the boss travels is relatively wide, said wider portion being considerably wider than the usual raceway groove, and being of sufficient width and depth throughout its 35 length to receive the neck or boss 16 of the buttons 6. The portion 19 of said groove in which the eye travels is made narrow, about the width of the ordinary raceway groove to receive the eye 5 of the button. That is, 40 the groove, viewed in transverse section, is of two widths, a narrow lower portion for the eye and a wider top portion for the boss.

The block in which the raceway groove 45 or channel is cut slopes downwardly from its upper to its lower end with relation to the bed 20 of the raceway until it finally thins down sufficiently so that the groove develops into a slot 21 through which the eye of the 50 button extends, and at the very lower end portion the said slot 21 is broadened out into an opening 22 of sufficient width for the passage of the boss 16 as well as of the eye 5 of the button. The said bed plate 20 of 55 the raceway is preferably of no greater thickness than the length of the boss or neck 16 of the button, and the edges 23 of said broadened portion 22 of the raceway slot are beveled to form a convenient seat for 60 the beveled sides of the boss 16.

The button fingers, or button carrier fingers, 24, 24, are for the purpose described in said former Patent No. 1,070,170, namely, to take the lowermost button in the raceway 65 at the proper time after the last previously

advanced button has been threaded with its fastener and carried to the anvil 52 and to advance said next following lowermost button to the proper position to receive the wire for the fastener. Said button carrier fingers 70 are slidably mounted respectively in a carriage in such manner that said fingers are slidable at right angles with the raceway and said carriage is slidable longitudinally of the raceway. In the form shown in the 75 drawings, the carriage consists of two blocks 25, 25, one on each side of the raceway, tied together by a yoke 26 which is arched over the top of the raceway and which is secured to the lower end of a rod 27, the other end 80 of said rod 27 being connected with suitable mechanism, not shown, for reciprocating said carriage up and down parallel with the raceway at the proper times. The form of said carrier fingers is an improvement upon 85 the form shown in said former patent.

The proximate ends 29 of said carrier fingers 24 are somewhat concaved and are undercut or formed with backwardly sloping faces 32. The proximate horns or corners 90 61, 61 on the upper side are nearer together than the proximate horns 62, 62 on the lower side, making a sort of concave flare. The purpose of having the upper corners more nearly together and of having a wider spread 95 of the lower corners, is so that when they first grip the button they will more positively separate it from the one behind it, and when the fingers separate to release the button it will be released more quickly, 100 and yet when in gripping engagement the button is securely held. When the said fingers grip the button 6, as shown in Fig. 3, the thin upper edges formed by the undercut of the fingers 24 will engage the button 105 head.

The button carrier fingers 24 are formed with laterally projecting stop portions or shoulders 34 to engage the outer sides respectively of the blocks 25 at the edge of the 110 slot in which the said fingers slide so as to prevent the said carrier fingers from being moved inward beyond a limited distance sufficient to grip the buttons. Pivotedly connected between ears on the lower end of 115 the raceway cover 2 by a pin 35 is a stop finger 36 which has a tension spring 38 to normally hold the lower end down in front of the lowermost button in the raceway, as shown in Fig. 1, so as to hold the line of 120 buttons in the raceway against movement until the proper time.

Two swinging finger cams 39, 39, one on each side of the raceway at a little distance therefrom, are fulcrumed respectively on 125 studs 40 which rise from the head of the machine, said cams having cam-faced portions 41 which are adapted to be engaged by pins 42, 42, respectively rising from the outer portions of the carrier fingers 24. A 130

spring 43 extends across above the raceway and is connected at its opposite ends with pins 44 rising from the finger cams 39. Said spring tends to draw the lower 5 arms of said cam fingers toward each other, but they are limited in their movement by the pins 45 rising from the head of the machine which engage the outer faces of the upper arms of the said finger cams. When 10 the carrier fingers are in their uppermost or rearmost position, the pins 42 which rise from the carrier fingers are on the inner sides of the finger cams 39, the concave inner ends of the carrier fingers being then in 15 engagement with the opposite sides of the lowermost button in the raceway. When the carrier fingers are moved down by the movement of the bar 27 said pins 42 engage the inner cam faces of the portions 41 of the 20 cams 39, thereby swinging the finger cams 39 on their pivots and spreading open the cam portions 41 so as to allow said carrier fingers to move downward with the button. When said carrier fingers have moved down 25 far enough for the pins 42 to ride past the portions 41, the spring 43 which will have become distended by the swinging movement of the finger cams, will contract and pull the finger cams back into normal position 30 to the limit allowed by the stop pins 45 which engage the rear arms thereof, while the carrier fingers will continue to the lower end of their stroke, namely sufficient to position the button as shown in Fig. 2. The 35 bar 27, and therefore the carrier fingers 24, will remain in their lowermost position holding the button until the proper time for returning the carrier fingers to the position to engage another button. The return movement 40 of the carrier fingers may occur at any time after the button has been threaded with the wire for the fastener. The actuating mechanism for the button finger carrier forms no part of the present invention, nor 45 do the fingers 39, but they are merely shown and described herein for convenience of understanding the use of the button carrier fingers.

It is to be understood that after the button 50 has been positioned as described, placer mechanism, which is not shown, comes into action to hold the said button in its position where left by the carrier fingers, and the carriage formed by the blocks 25 and the 55 yoke 26 will be moved backward. During the initial rearward movement the rounded edge of the button will form a cam surface which will spread slightly the said carrier fingers until they move away from the button 60 ton, then the pins 42 which rise from the carrier fingers will engage the outer faces of the cam portions 41 and spread the carrier fingers apart from each other against the tension of the spring 47 until the said 65 pins 42 have ridden up past the rear ends of the cam portions 41, whereupon said springs 47 will cause the carrier fingers to snap in toward each other and engage the lowermost button in the raceway above the button which has just been released by the 70 carrier fingers. Said lowermost button which is thus engaged is then just above the stop finger 36, as shown in Fig. 1, thus gripping the button ready for the next downward movement of the carrier fingers. 75 When the carrier fingers move down again they grip the button with sufficient firmness so that the pressure of the button will turn the stop pin 36 on its pivot so that the button can ride beneath it. 80

The raceway cover 2 is made adjustable to allow for varying sizes of buttons. The supporting and adjusting mechanism will now be described. The said cover 2 is provided near its upper end with two opposite 85 and downwardly extending ears or legs 48 which engage with and are vertically slideable in grooved guide ways in the side guide plates 49, 50, which are fixed to the bed 20. Rising from the top of the cover is a boss 90 51 which is tapped out to receive the threaded stem 52 of an adjusting screw. Said adjusting screw is formed with a peripheral groove 54 between the two flange portions 53, 53. The side guide 50 extends upward 95 higher than the cover of the raceway and has at its upper end a bifurcated flange 55 whose arms embrace the neck of the adjusting screw between the said two flanges 53, 53. The said adjusting screw is formed 100 with a head 56, preferably knurled, so that the adjusting screw may be easily turned. Inasmuch as the side guide 50 and the over-reaching arm 55 are stationary with relation to the bed on which the raceway is 105 mounted, when the said adjusting screw is turned, said screw will not rise or fall, but instead it will raise or lower the raceway cover, according to which way the said adjusting screw is turned. Inasmuch as the 110 legs 48 of the cover fit within the groove and guide ways, although said grooves allow the cover to be raised and lowered, the cover is not capable of any oscillating movement but is held rigidly so that when the adjusting 115 screw is turned, the entire cover will be correspondingly raised or lowered.

What I claim is:

1. In combination with a button raceway, a reciprocable carriage having portions movable parallel with the raceway on each side thereof, two slidable fingers mounted on opposite sides of the raceway in said slidable carriage members, and slidable laterally with relation to the raceway and with relation to said carriage members, and tension mechanism which causes the said fingers to move toward each other and to grip a button in the raceway, said fingers being formed with their proximate ends concaved on their 120 125 130

upper edges, the horns of the concave ends on the entrance side being nearer together than the horns on the exit side.

2. In combination with a button raceway, 5 a reciprocable carriage having portions movable parallel with the raceway on each side thereof, two slidable fingers mounted on opposite sides of the raceway in said carriage members and slidable laterally with relation 10 to the raceway and with relation to said carriage members, and tension mechanism which causes the said fingers to move toward each other and to grip a button in the raceway, said fingers being formed with their 15 proximate ends concaved on their upper edges, the horns on the entrance side formed by the concave ends being nearer together than the horns on the exit side, said proximate ends being under cut and sloping down- 20 wardly and backwardly.

3. In combination with a button raceway, two button carrying fingers adapted to embrace a button on opposite sides thereof, said fingers being formed with their proximate 25 ends concaved on their upper edges, the horns formed by the concave ends on the entrance side being nearer together than the horns formed on the exit side.

4. In combination with a button raceway, 30 a cover therefor having on two opposite sides thereof downwardly extending arms, two side members rising respectively at op-

posite sides of said raceway and formed with 35 guide grooves in which said arms are fitted to slide up and down with relation to the raceway, an adjusting screw, and a mount overhanging the raceway cover in which said 40 adjusting screw is rotatably mounted, said mount being fixed with relation to the raceway, said adjusting screw having threaded connection with said raceway cover whereby by turning said screw said cover may be raised and lowered uniformly throughout its length.

5. In combination with a button raceway, 45 a cover therefor having on two opposite sides thereof downwardly extending arms, two side members rising respectively at opposite 50 sides of said raceway and formed with guide grooves in which said arms are fitted to slide up and down with relation to the raceway, an adjusting screw, and a mount for said screw overhanging the raceway cover, said screw having a shank formed with an annular 55 groove, and said mount having a flange portion which engages with said annular groove whereby said adjusting screw is permitted to be rotated and is held against a longitudinal movement during its rotation, said screw having threaded connection with the 60 cover of the raceway whereby by turning the screw the cover will be raised and lowered.

In testimony whereof I affix my signature.

GEORGE W. PERKINS.
